UNITED STATES PATENT OFFICE.

ROBERT OWEN ALLSOP, OF LONDON, ENGLAND.

PETROLEUM-ENGINE.

No. 868,392.

Specification of Letters Patent.

Patented Oct. 15, 1907.

Application filed November 6, 1906. Serial No. 342,070.

To all whom it may concern:

Be it known that I, ROBERT OWEN ALLSOP, a subject of the King of Great Britain and Ireland, residing at London, England, have invented Improvements in 5 Petroleum-Engines, of which the following is a specification.

The object of this invention is to provide an improved form of, and method of constructing, the fuel inlet valve for petroleum engines having a fuel vapor pump such as are described in the specification of Letters Patent No. 725191 dated 14 April, 1903, but the invention is also useful in connection with other suitable types of internal combustion engine.

Usually in petroleum engines having a fuel vapor 15 lamp the fuel has been admitted through a single hole in the seating of the pump inlet valve.

According to this invention the fuel is admitted through a fine passage at more than one point in the valve seating. The valve is made with more than 20 one hole in the seating and the valve box is specially constructed so that the said holes may be easily made of any degree of fineness; as an alternative, a continuous fine groove or slit may be formed in the seating in place of the holes or isolating channels.

25 This invention I find by trial constitutes a very great improvement in engines of the type referred to. The objection to having one hole only is that, if this single hole be very fine, insufficient fuel passes, while, if large, the fuel is ineffectually atomized, and a large 30 portion enters the pump in liquid form.

I preferably carry out my invention in the following manner:—I make the pump fuel inlet valve box in two parts, suitably secured or bolted together. The line of junction between the two parts cuts the valve 35 seating preferably on the center of the seating and preferably at right angles to such seating. The two jointing places are accurately and closely fitted together preferably by grinding. In the joint face thus formed I turn a small groove or channel; I suitably 40 connect this groove to the petroleum supply. From the said groove I form, in the joint faces, suitable small grooves or cuts of suitable number, which, when the joint faces of the valve box are secured together, form fine holes in the seating suitable to produce, by 45 the innrush of air through suitable passages, perfect atomization of the fuel. These holes are stopped by the valve when held up to its seating by its spring, and the fuel supply automatically ceases when the engine stops. In place of the fine grooves, one joint face 50 may be slightly turned down so as to leave a fine continuous slit for the fuel to pass, but I preferably employ the isolated grooves, which, in effect, form fine holes.

I control the fuel supply to my improved valve, 55 either by a suitable needle valve, when I wish to employ simple pressure or gravity feed, or by a suitable

“float feed” if I wish to maintain a vapor supply that may be equal or approximately equal, per piston stroke independent of the speed of the engine. I suitably connect the “float” feed to the valve, preferably 60 by making the float chamber and part of valve-box as one casting.

The accompanying illustrative drawings show my invention and the manner of carrying out the improvements.

Figure 1 is an elevation of the complete valve. Fig. 2 a plan, Fig. 3 a section and Fig. 4 a plan of lower part of valve casing, all of the preferred construction. Fig. 5 is a part sectional elevation similar to Fig. 2 of a modification.

A is a casting forming the lower part of the valve box; B is the upper portion of the valve box; and C is a nut or union cap drawing the two parts of the valve together; D is the valve held to its seating by a suitable spring; E is the entry for petroleum, being a 75 tapped hole into which can be screwed a controlling needle valve. As shown, the junction line of the upper and lower parts of the valve box occurs in the center of the valve seating. The lower valve box part is bored as a guide for the parallel portion of the upper 80 valve box part.

F, F are holes for the admission of air.

A hole G is drilled to meet the petroleum entry and is continued until it meets the junction faces of the two parts of the valve seating H and a channel J is turned 85 in one or the other or in both of the valve box faces. In Fig. 3 it is shown as turned in the part A.

The hole, G, being plugged as shown, the petroleum can find its way from the entry to the circular turned channel. Fine channels or grooves K, are formed between the circular channel and the valve seating either in one or the other or partly in both parts of the valve box but shown in Fig. 3 as formed in the part A. These grooves are preferably made with a fine three-cornered file, or they may be formed with a graver or other suitable tool by hand or by machine. The two parts of the valve box being screwed together by the cap, the petroleum can now find its way through the grooves which, when the parts of the valve are put together become virtually fine holes. When the valve is lifted off its seating by the suction of the pump piston the petroleum is sprayed—by the air entering holes F—on to the hot surface of a vaporizer which for example may be exhaust-heated and located over the fuel vapor pump of the engine. By this construction the advantage of 100 very fine passages as regards effective atomization of the liquid fuel is secured without the practical difficulty of exceedingly fine drilling, while upon taking the valve box apart the grooves can be easily cleaned.

As previously mentioned instead of the channels or 110 grooves K a continuous fine groove or slit L may be formed in the seating by turning down the joint face of

the upper or lower part of the valve as for instance shown in Fig. 5 where said groove or slit as well as the turned channel J are formed in the part B.

What I claim is:—

- 5 1. In an internal combustion engine, a fuel valve comprising a valve box part having a valve seat portion, another valve box part provided with the other seat portion, co-acting junction faces between the valve box parts, grooves in one of such faces leading to the valve seat, a 10 channel communicating with said grooves, and, a fuel supply passage connected with the channel.
2. In an internal combustion engine, a fuel valve comprising a valve box part having a valve seat portion, another valve box part provided with the other seat portion, 15 co-acting junction faces between the valve box parts, said junction surfaces extending to the valve seating at right angles thereto, an annular groove formed in one junction face and a number of notches formed in either junction face communicating with the valve seating and the annular groove and a passage for the supply of fuel to the latter.
3. In an internal combustion engine, a fuel valve comprising a valve box part having a valve seat portion, another valve box part provided with the other seat portion, co-acting junction faces between the valve box parts, said 20 junction faces extending to the valve seating at right angles thereto, an annular channel formed in one junction face and a number of notches formed in either junction face communicating with the valve seating and the annular

groove, a passage leading from the channel to the fuel supply and means for securing the two portions of the valve 30 box together.

4. In an internal combustion engine, a fuel valve comprising a valve box part having a valve seat portion, another valve box part provided with the other seat portion, co-acting junction faces between the valve box parts, said 35 junction faces extending to the seating at right angles thereto, a union nut for drawing said parts into close contact and means whereby fuel can be introduced through the valve seat uniformly therearound.

5. In an internal combustion engine, a fuel valve comprising a valve box part having a valve seat portion, a ground face at right angles to the seat portion, an annular channel in said face, passages radiating from such channel and extending through the valve seat portion and a passage leading from the channel to the fuel supply, a valve 40 box part fitting within the first named part, a ground face and valve seat portion co-acting with the face and valve seat portion aforesaid, a union nut for maintaining such faces in contact, a valve seated on both seat portions and ports for supplying air to one side of the valve. 50

Signed at London England this 25th day of October 1906.

ROBERT OWEN ALLSOP.
